CONTACT ROLL CONSTRUCTION

John S. Nachtman, Youngstown, Ohio

Original application January 16, 1939, Serial No. 251,065, now Patent No. 2,341,157, dated February 8, 1944. Divided and this application January 24, 1944, Serial No. 519,429

5 Claims. (CL 204—211)

1

This invention relates to electro baths, and particularly, to the handling of strip material while subjecting it to an electro-treating process, such as electroplating. I have particular reference to suitable contact roll apparatus for continuously electroplating or treating metal strip and the like; and this application is a division of my copending application Serial No. 251,065, filed January 16, 1939, now Patent No. 2,341,157, granted February 8, 1944.

I have found that there are many difficulties encountered in providing a suitable arrangement for the purposes enumerated. In electro treatment, the strip will constitute one of the electrodes (in plating, the cathode) and other means will constitute the other electrode (in plating, the anode).

The contact roll apparatus of the prior art possesses the following serious disadvantages, among others, which have made it impractical to produce a uniformly high grade product by a continuous operation:

(a) In continuous plating operations, high current densities per unit of surface being plated must be employed to expeditiously deposit coatings of desired thickness; and, great lengths of strip must be subjected to the plating operation for comparatively long periods of time. The length of strip being subjected to the plating operation at any one instant may in practice, be several hundred feet. In order to plate such a length of strip while in motion, the strip being the cathode, it is necessary to establish electric contact with it at a number of points spaced along its length. This is usually done by reeving the strip over two sets of rolls, an upper set and a lower set, contact for the plating current being made through the upper set of rolls, over which the strip passes. With this arrangement it is difficult to obtain a good electrical connection between contact rolls and the metal strip, especially after the strip has been partially plated. The strip passes approximately half-way around the contact roll or rolls (upper set), and as it is wet with the electrolyte, the current, in going from the roll to the strip, must pass through a thin film of electrolyte. This causes deposition of metal on the roll instead of the strip, and may even remove plated metal from the strip while passing over the roll. This is undesirable, as it is detrimental to the apparatus and makes it impossible to obtain a high grade product.

(b) Pulling the strip from one end thereof over a number of rolls subjects it to high flexing and tensional stresses. This is true even if the

2

rolls are turned without friction, but as the current is conducted to the rolls through a slip ring or brush system, which increases the resistance to turning of the rolls, the strip tension is of considerable magnitude. If the rolls must be turned by friction with the strip, slip of strip where it makes contact with the rolls may occur. If the strip surface is soft as for example electroplated with a soft metal such as tin, any such slip may damage the plating, especially in the initial stages, where the plating is very thin, and may not have completely covered the base stock of the strip.

(c) The contact rolls themselves are particularly weak portions of such an apparatus and are a constant source of trouble because of limitations in material available for their construction. Those that are made of material that possesses good electrical properties and have sufficient mechanical strength to withstand the stresses to which they are subjected in carrying the strip, usually are subject to corrosion by the electrolytes; whereas, those that are constructed of good corrosion-resisting materials such as carbon and some cast alloys, are usually not good conductors and do not possess sufficient mechanical strength to withstand the stresses in carrying the strip.

(d) Also, serious difficulties are experienced in making electrical contact between rotating contact rolls over which the strip passes, as heretofore constructed, and the stationary current-supplying brushes because the contact surfaces are exposed to the electroplating solution. This causes a loss in voltage, which results in excessive heating and other contact ills. This condition is further aggravated because many of the most desirable solutions in use today react electrolytically with the brushes.

It is accordingly a general object of my invention to provide a commercially practical solution of the difficulties and problems presented in prior art contact roll construction.

Another object of the invention is the provision of contact roll apparatus for continuously electroplating strip material that will efficiently and uniformly conduct electroplating currents thereto at several regions throughout its length as the strip passes through the bath or baths, with a minimum of resistance.

A further important object of the invention is the provision of an improved contact roll construction for electroplating strip material continuously that employs a plurality of rolls, driven at a suitable synchronous peripheral speed for gripping the strip at spaced points throughout

its length and smoothly propelling the strip through the electroplating steps without subjecting the strip to tensional or twisting forces.

A further object is to provide a novel contact roll construction for use in electroplating or electrochemical processing apparatus and which embodies a totally enclosed current-conducting mechanism which is not contaminated by the electro-bath solution.

A still further object is to provide a hollow contact roll for use in electroplating apparatus for strip material which embodies internal brushes contacting an inner surface of said roll at a region in proximity to the point of contact of the strip material with the outer surface of the roll, whereby the path of current through the wall of the roll is of minimum length and the brush pressure counteracts the pressure against the outer surface of the roll.

Moreover, it is an object of the present invention to provide a novel contact roll construction for use in electroplating and electrochemical processing apparatus, which embodies an enclosure for the current conducting brush mechanism through which cooling fluid may be circulated.

These and other objects of my invention will appear to those skilled in the art from the drawings, the description, and the appended claims.

Although for the purpose of illustration I particularly refer to electroplating operations, it should be understood that many of the novel features of this invention are equally applicable to electro-pickling and other types of electro-bath treating operations.

In the drawings,

Figure 1 is a fragmentary vertical sectional view through electroplating apparatus embodying the improved contact roll construction;

Fig. 2 is a fragmentary vertical longitudinal sectional view taken substantially along the line 2—2 of Fig. 1, looking in the direction of the arrows;

Fig. 3 is a longitudinal sectional view through the contact roll construction employed in the apparatus of Figs. 1 and 2;

Fig. 4 is a transverse sectional view taken on the line 4—4, Fig. 3;

Fig. 5 is a longitudinal sectional view similar to Fig. 3, but illustrating a modified form of contact roll of the invention; and

Fig. 6 is a transverse sectional view taken on the line 6—6 of Fig. 5, looking in the direction of the arrows.

Similar numerals refer to similar parts throughout the various figures of the drawings.

The apparatus comprises a tank or container T through which the strip material S is fed in a sinuous path. The strip material is reeved over and under respectively, a series of upper rolls 7 and 8 and lower rolls (not shown) submerged in the solution in the tank; the rolls 7 and 8 being above the surface of the solution.

Above the strip where it passes over each roll 8 is a contact roll 1, by means of which electrical contact for the plating current is made with the strip, instead of through roll 8, as is the practice usually followed hitherto. The rolls 7 are preferably driven at the same peripheral speed so as to propel the strip smoothly through the bath. As the strip emerges from the bath for the last time, it passes through a squeegee assembly Q for removing the adhering electrolyte therefrom.

An anode electroplating current is applied to a plurality of anodes A which are suspended in the bath between the vertical reaches of strip S.

The electrolyte is continuously circulated, preferably, by removing a portion of it from tank T, filtering it, passing it through a heat exchanger (for imparting heat thereto or dissipating heat therefrom, as the case may be, for securing the requisite electroplating temperature), and returning it to tank T at a point remote from the removal point. The electrolyte is returned to electroplating tank in such manner as to continuously agitate the body of the electrolyte in the tank adjacent the anodes A and also to flush strip S above the level of the electrolyte for dislodging adhering extraneous matter, both as it is entering and emerging from the electrolyte.

10 The tank T is generally rectangular in form and comprises side walls, a bottom wall and end walls. For the purpose of simplifying the illustration of the invention, I have shown the strip as making only two complete passes through the electrolyte, but it is to be understood that in actual practice the tank and other parts will be so designed as to cause the strip to make any suitable number of passes through the electrolyte; in some instances several hundred feet of strip material may be immersed in the tank at one time.

15 A circulation pipe communicates with the bottom of the tank through which the electrolyte is fed to an electrolyte reconditioning and heat exchanging apparatus, of any suitable character, 20 for purifying the electrolyte, restoring it to proper strength and bringing it to the requisite electroplating temperature.

The electrolyte is returned to the tank by way of a pair of spray pipes 9 and a pair of recirculation pipes 10. Spray pipes 9 may extend longitudinally of the apparatus and they are joined by a plurality of pairs of perforated pipes 11. The pipes of each pair are disposed either side of the path of travel of the strip S and the perforations 40 are directed downwardly at an angle to the horizontal for flushing the strip and cleansing it of any adhering material. Pipes 10 are each joined to a horizontal pipe 12 and, as seen in Fig. 1, each pipe 12 extends longitudinally on either side of the path of travel of strip S. Joined to pipes 12 at spaced intervals are vertical pipes 13, each having perforations 14 therein that are directed toward the middle of the tank. The electrolyte issuing from openings 14 supplies fresh electrolyte adjacent the anodes and also keeps the body of the electrolyte in the tank in a state of constant agitation.

50 The contact roll assemblies and other parts of the mechanism are carried upon a pair of horizontally extending angle members 15, which extend longitudinally of the apparatus and rest upon a plurality of vertical supports 16. The mechanism preferably is supported upon the independent framework just described in order that the tank may not be subjected to stresses. The tank may, accordingly, be constructed of wood, concrete, brick, steel, hard rubber, or any other material or combination of materials appropriate for use with the particular electrolyte employed, without special regard for supporting the assemblies and parts. To this end, the bus bars and anodes are also supported upon an independent structure to be hereinafter described.

55 The contact roll assemblies shown in Figs. 1 to 4, inclusive, are similar in construction and therefore one of them will be described.

60 Each assembly comprises a contact roll 1, proper, which is mounted for movement to and from an associated strip carrying roll 8.

65 Referring to Figs. 1 and 3, each contact roll

7 is journaled on a shaft 17, which is carried at each end thereof in an arm 18, which in turn is pivoted at 19 upon the support 20, carried by members 15. Shaft 17 is insulated from members 18 by means of insulating bushings 21, and an electrical conductor 22, preferably of flexible design, is connected to each end of shaft 17 for applying a cathode current to shaft 17 and to contact roll 7 in a manner later to be set forth.

Each strip-carrying roll 8 is preferably made of steel and rubber (resilient) covered in order that it may effect intimate surface engagement between the strip S and the contact roll 7. The provision of a coating or cover that will yield under pressure is an important feature of the present invention; it is preferably an insulating material. However, the invention is not limited to the use of such materials, as the surfacing of the carrying roll may be constructed of any other material found suitable for the purpose such as phenolic condensation product impregnated fiber, asbestos or other materials or combination of materials. Each carrying roll is supported on a shaft 23, which latter is journaled at each end in a bearing carried by the support 20. A slinger 24 is positioned on shaft 23 adjacent each side end of the carrying roll; it functions to keep the electrolyte (with which the carrying roll is coated in normal operation by reason of the strip carrying it out of the tank) from creeping along the shaft and into the bearings.

Each contact roll 7 is resiliently urged toward a carrying roll, preferably by means of compression springs 25 that act upon extensions 26 of the arms 18. Each extension 26 is apertured and a stud 27, secured to the support 20, extends through the aperture and through spring 25 and has a nut 28 threaded thereon, against which the spring 25 abuts. By adjusting nut 28 of each contact roll assembly, the strip can be gripped between surface portions of the contact roll 7 and strip carrying roll 8 in contact with the strip with various degrees of compression. A second compression spring 29 is shown on each stud 27 between extension 26 and support 20 for opposing the action of spring 25 and smoothing out the gripping action of the contact roll assemblies.

Each contact roll 7 is preferably hollow and provided with novel means for conducting the cathode current from the stationary shaft 17 to the roll; Figs. 3 and 4 show a construction of the parts.

Secured to the shaft 17 by a pair of set screws 30 is a pair of flanged collars 31. Journaled on each collar 31 by means of a bushing 32 is a driven annular-like support member 33 having a slinger 34, and a reduced cylindrical portion 35 terminating in a seal 36; the latter cooperates with shaft 17 to prevent electrolyte from finding its way into the interior of the drum. The drum supports 33 are preferably made of an insulating material. Extending transversely between and joining each pair of members 33 is a cylindrical shell or drum 37; it is secured thereto by a plurality of cap screws 38. Drum 37 is preferably a seamless copper tube, but it may be made, if desired, of other suitable materials without departing from the spirit of the invention. A nickel sleeve surface plate 39 is preferably welded to the periphery of drum 37 and is adapted to directly contact the strip S as it passes between the contact rolls. Fitting tightly over the opposite ends of sleeve 39 and welded thereto is a further pair of slinger rings 40 for throwing the electrolyte clear of the ends of the rollers.

Each contact roll 7, accordingly, is mounted for free rotation on shaft 17. I employ novel totally enclosed brush means for conducting a substantially uniformly-distributed cathode current to the contact roll 7 throughout its length in a manner that now will be set forth. Secured to shaft 17, by means of cap screws 41, are a plurality of brush support members 42 that may be of cast construction. Each member 42 is provided with a plurality of brush guide openings 43; the brushes 44 are mounted therein to cooperate in direct frictional engagement or contact with the interior of the inner wall or circumferential surface of the drum 37. A flexible brush lead 45 is connected to each brush 44 and is secured to shaft 17 by means of a cap screw 46. Each brush 44 is resiliently urged toward the surface of the drum by means of a leaf spring 47; one end of the spring 47 is coiled within a support 48, carried by member 42 and its free end 49 is adapted to be selectively placed in one of the plurality of slots in support 48, for selectively varying the pressure applied to its brush.

From a consideration of Figs. 2 and 4, it is apparent that brushes 44 apply current to the interior of the drum 37 in the same region as that where the strip contacts the outside of the drum. Therefore, as brushes 44 are comparatively numerous and are uniformly distributed along the transverse length of the drum, the current path through the drum to the strip is of large cross section and short length, which makes for minimum resistance and current loss and avoids heating of the parts in service.

Another important feature of the contact roll 7 construction just described resides in the fact that the load of carrying the strip is totally absorbed by the carrying roll 8 and no severe stresses are imparted to the contact roll. The pressure exerted upon the contact rolls 7 is that set up by springs 25; in this manner an electrical and driving frictional contact is provided between the roll and the strip. The brush pressure on the inside of the roll 7 tends to counterbalance the strip contact pressure on the outside of such roll.

The contact drum therefore is substantially free from strain under service-conditions, and this permits the use of even relatively brittle materials, such as cast alloys and carbon, etc., which are highly resistant to corrosion by electroplating solutions.

The contact roll supports 33 are preferably constructed of an insulating material which functions as an insulator to prevent current from passing to the roll by way of the bearings.

In ordinary service, the parts efficiently function at sufficiently low operating temperatures, but in the event that the solutions to be employed are hot, a cooling medium may be circulated through the roll, and in Fig. 3 there is illustrated one mode for effecting such a result.

In Fig. 3 the shaft 17 is hollow and is provided with a cooling medium inlet at its left hand end. In the interior of the roll 7, the shaft is provided with a plurality of ports 50, through which the cooling medium is adapted to discharge and circulate amongst the brushes in the left hand end of the roll. A plug 51 of any suitable material is secured within shaft 17, approximately midway of its length, by means of a tapered pin 52, to prevent the cooling medium from flowing freely from one end of the shaft to the other.

The cooling medium may be any desired fluid, such as cold, dry, compressed air, and after it 75 has passed through ports 50 and has abstracted

heat from the brushes in the left hand end of the roll, it circulates amongst the brushes in the right hand end of the roll and is exhausted through a plurality of exhaust ports into the right hand end of the roll and is freely discharged therefrom or through a manifold assembly (not shown) to an air cooler at the suction side of the compressor used.

When it is desirable to operate the contact roll at an elevated temperature, as is the case in plating some of the metals (iron, for instance), there is likely to be metallic oxidation formed on the inside of the drum 37, thus causing a high contact resistance between the brushes 44 and the drum 37. I overcome this trouble by injecting a sufficient quantity of a suitable oil to submerge the contact area between the brushes 44 and the drum 37. The oil performs two functions. (1) It coats the inside surface of the drum 37, thus excluding air and preventing oxidation of the inside surface of the drum. (2) It also lubricates the sliding contacts between brushes 44 and drum 37 without materially affecting the contact resistance between the brushes and the drum.

The gripping or clamping pressure exerted by springs 25 of the various contact rolls upon the strip may be equal or unequal as desired, depending upon the current to be conducted to the strip and other factors involved. The strip material is looped beneath the submerged rolls in the electrolyte.

The various contact rolls, whether they are of equal or unequal diameter, are driven at a synchronous peripheral speed by any suitable means, in order that all parts of the strip material will be smoothly propelled through the bath. If driving of the contact roll by contact with the moving strip causes undesirable strip tension, a drive sprocket 54 may be secured by means of a key 55 and set screw 56 to the reduced end of one of the drum support members 33, as shown in Fig. 3; and the drive sprocket 54 may be driven by means of a sprocket chain from a drive motor for each contact roll, the motors being synchronized to insure smooth propulsion of the strip through the bath.

Referring to Figs. 1 and 2, a secondary framework having uprights 57 and horizontally disposed angle members 58 is employed to support the bus bar and anode assembly as follows:

Supported on an insulator assembly 59 and carried by members 58 at each side of the tank are a plurality of transversely extending anode supports 60 that extend across the tank as shown in Fig. 1. A plurality of anode bars A are secured to supports 60 and are submerged in the electrolyte. As seen in Fig. 2, some of the anodes A are located adjacent the downwardly (outer) facing portions of the loops formed by the strip material in the electrolyte and they therefore operate to effect electroplating of the underside of the strip material. Other anodes A are disposed within the upwardly (inner) facing loops of the strip material and electroplate the upper surface of the strip material. The two groups of anodes preferably are electrically segregated in order that a different plating current can be applied to one group or the other to effect a different electroplate on one surface of the strip.

Supports 60 for some of the anodes A accordingly are connected at each side of the tank to a bus bar 61 carried in a plurality of insulators 62, which in turn are carried by a plurality of brackets 63 secured to supports 57. Supports 60 for other anodes A extend outwardly beyond bus 78

bars 61 and are connected to bus bars 64, which also are carried by insulators 62.

In Fig. 5 a modified form of contact roll is shown, the major differences between it and the contact roll shown in Figs. 3 and 4 residing in the fact that the brushes are pivoted rather than slideable in their holders, that a modified cooling arrangement is used, and that anti-friction bearings are used.

10 A pair of annular-like spaced-apart drum supports 65 are journaled on bearings 66 and 67 on shaft 17a; and a cylindrical drum shell 68 having integral slingers 69 is secured to the drum supports by a plurality of cap screws 70. A pair 15 of sealing assemblies 71 are associated with drum supports 65 and cooperate with shaft 17a to prevent lubricant from leaking from the bearings into the brushes. A drive sprocket 72 is mounted on one of the drum supports for imparting rotation thereto.

20 Shaft 17a is provided with a flat-sided lower surface 73 (see Fig. 6) that extends as shown in Fig. 5. Firmly clamped to shaft 17a by means of screws 74 are a plurality of brush supports 25 75. Each brush support carries a pair of brushes 76, which cooperate with the inner surface of the drum. Each brush is carried by an arm 77 pivoted at 78 on the brush support, and is urged 30 toward the drum by torsion spring 79. The brush supports also embody notched sectors 80 so that the brush pressure may be adjusted by placing the free ends of the springs in the appropriate notches to give the requisite pressures. In order to prevent pivots 78 from carrying current, a 35 flexible shunt cable 81 is connected directly to each brush through the brush support.

40 The current is supplied to shaft 17a by a flexible conductor in a manner similar to that shown and explained in the embodiment of my invention disclosed in Figs. 3 and 4. The contact roll is also preferably cooled by a fluid medium which enters a conduit 82 at one end of shaft 17a, passes through a longitudinally extending bore 83, and is exhausted through a plurality of 45 ports 84 provided in shaft 17a. The cooling medium may be dry, cold, compressed air; it passes downwardly in the roll along both sides of the shaft 17a and abstracts heat from the brushes and their associated parts. The heated air is 50 exhausted from the roll by way of a plurality of exhaust ports 85, which communicate with a longitudinal passage 86 provided in the shaft; passage 86 communicates with a discharge conduit 87.

55 In this form of the invention, the brushes are completely enclosed and protected against the action of the electrolyte, they are arranged substantially uniformly along the axis of the roll, and they are urged outwardly against the inner 60 surface of the roll in the region where the outer surface thereof contacts the strip under a pressure that is substantially equal to the contact pressure of the roll with the strip. Therefore, 65 all of the advantages of the previously described form of contact roll are achieved.

It will be apparent to those skilled in the art that the contact rolls of my invention can be employed with advantage in place of contact rolls heretofore used in the art, but that I prefer a roll pair combination such as 1 and 3, in order to incorporate desirable features of such a roll pair. However, if a contact roll is employed without a strip-carrying roll, I prefer to keep the diameter of the contact roll as small as possible;

e. g., a single roll may be used in electro cleaning.

Although I have illustrated the invention in connection with the electroplating of strip material in the form of steel or other metallic sheets, it is to be understood that the novel features thereof are applicable to the electroplating of wire, cable, sheet and elongated shapes and/or articles. The appended claims therefore embrace my invention as applied to any suitable form of material, designated, generally as "strip."

Also, the contact roll assembly of the invention may be embodied in equivalent forms without departing from the spirit of the invention. For instance, the brushes may be secured to the inner surface of the drum and may cooperate frictionally with the stationary shaft. Also, I have illustrated the cathode current-carrying roll as constituting the roll that is movable toward and away from the carrying roll under the influence of spring pressure, but it is to be understood that the relationship may be reversed and the carrying roll be movably mounted and resiliently urged upwardly toward the novel current-carrying roll constructions of the invention. Also, the roll that has been referred to as the carrying roll may embody the novel enclosed brush combination of my invention.

The cooling apparatus is especially advantageous where excessive heat is encountered. The use of the cooling system is also advantageous, because by suitably regulating the input and output pressure of the cooling medium, a positive pressure may be maintained in the contact roll during operation such that corrosive fumes and gases evolved from the electrolyte will be prevented from creeping along the shaft and attacking the bearings.

The novel contact roll assembly of the invention effects an improved method of applying the cathode current to the moving strip, because the thin and highly conductive shell constituting the drum makes a line contact with the strip to be plated, and because the brushes bearing against the interior of the shell along a line in approximate super-position with the line of contact of the shell with the strip, insures a uniformly distributed current throughout the length of the roll, with a resistance path of minimum length and with the total brush pressure substantially equal to the total pressure of the roll upon the strip. As a result, the shell is subjected to a minimum of distorting stress throughout the operation.

Thus, important features of the present invention in the improved contact roll construction are the enclosing of the brushes to protect them from contact with either the plating solution or vapors, the circulation of a cooling fluid through the contact rolls, and the brush contact aligned with the contact of the roll with the strip.

An ideal contact roll would be one which would not become heated by the current it conducts. It is of course impossible to make usch an ideal contact roll, but the design of improved contact roll disclosed herein, with the brushes in a row on the inside of the roll directly opposite to the line of contact between the roll body and the strip, approaches the ideal condition, as the path of current is very short and the current is concentrated in a relatively small portion of the roll. Also the only part of the roll body which is heated by current is in direct contact with the strip

and with solution, and therefore, the heat which is generated is taken away rapidly.

Entirely different conditions occur when the roll body is extended and the brushes contact the extended end of the roll. In such a construction, the length of the path of current is increased many times, the cross section is diminished and the portion of the roll where the most heat is generated never comes in contact with either the strip or the plating solution, and consequently a considerable temperature rise is experienced.

By actual calculation it can be shown that the heating effect in the roll body may be of the order of many times greater in a roll with brushes outside of the roll body as compared with a roll with brushes located inside the roll body directly opposite the line of contact between the moving strip and the roll.

The term "electrochemical processing" as used herein and in the claims, includes any electrochemical treatment of a moving metallic strip wherein the strip is connected to an electric potential which causes the electrochemical action on the strip.

I claim:

1. In electroplating apparatus for continuous strip, including a guide roll for the strip adapted to receive the strip against the surface thereof and to supply electric current thereto, said roll comprising a rotatable cylindrical metallic shell, a stationary electrically conducting shaft extending axially through the shell, means closing opposite ends of the shell around the shaft and including bearing means journaling the shell on the shaft, and brushes fixed to the shaft in electrical contact therewith and in outwardly bearing contact with the inner surface of the shell along a line adjacent the line of contact between the shell and the strip for supplying current thereto.

2. In electroplating apparatus for continuous strip, including a pair of opposed coacting rolls adapted to receive the continuously moving strip therebetween, one of said rolls comprising a rotatable cylindrical metallic shell, a stationary electrically conducting shaft extending axially through the shell, means closing opposite ends of the shell around the shaft and including bearing means journaling the shell on the shaft, and brushes fixed to the shaft in electrical contact therewith and in outwardly bearing contact with the inner surface of the shell along a line adjacent the line of contact between said rolls for supplying electric current thereto.

3. In electroplating apparatus for continuous strip, including a pair of opposed coacting rolls adapted to receive the continuously moving strip therebetween, one of said rolls comprising a rotatable cylindrical metallic shell, a stationary electrically conducting shaft extending axially through the shell, means closing opposite ends of the shell around the shaft and including bearing means journaling the shell on the shaft, brushes fixed to the shaft in electrical contact therewith and in outwardly bearing contact with the inner surface of the shell along a line adjacent the line of contact between said rolls for supplying electric current thereto, and means for circulating a cooling medium into the shell in cooling relation to the brushes and for discharging said medium therefrom through the shaft.

4. In electroplating apparatus for continuous strip, including a pair of opposed coacting rolls adapted to receive the continuously moving strip therebetween, one of said rolls comprising a ro-

11

rotatable cylindrical metallic shell, a stationary electrically conducting shaft extending axially through the shell, means closing opposite ends of the shell around the shaft and including bearing means journaling the shell on the shaft, brushes fixed to the shaft in electrical contact therewith and in outwardly bearing contact with the inner surface of the shell along a line adjacent the line of contact between said rolls for supplying electric current thereto, said shaft having spaced longitudinally extending passageways therein in open communication with the interior of the shell about the brushes, and means for circulating a cooling medium through one of said passageways into the shell and for discharging said cooling medium through the other of said passageways therefrom.

5. In electroplating apparatus for continuous strip, including a pair of opposed coating rolls adapted to receive the continuously moving strip therebetween, one of said rolls comprising a rotatable cylindrical metallic shell, a stationary electrically conducting shaft extending axially through the shell, means closing opposite ends of the shell around the shaft and including bearings journaling the shell on the shaft for turning movement relative thereto, said bearings being confined within the closing means for retaining lubricant therearound, and brushes fixed to the

15

20

25

12

shaft in electrical contact therewith and in outwardly bearing contact with the inner surface of the shell along a line adjacent the line of contact between said rolls for supplying electric current thereto.
